(57) **CLAIM**

The ornamental design for a laundry detergent pod as shown and described.

DESCRIPTION

FIG. 1 is a front, right-side, and top perspective view of a laundry detergent pod showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dashed broken lines depict portions of the laundry detergent pod for which no design protection is claimed.
